JOSEPH MARSHALL, OF LONDON, ENGLAND.

SIGNALING APPARATUS.

1,326,522.

Specification of Letters Patent. Patented Dec. 30, 1919.

Application filed January 23, 1917, Serial No. 144,019. Renewed November 12, 1919. Serial No. 337,838.

To all whom it may concern:

Be it known that I, JOSEPH MARSHALL, a subject of the King of Great Britain, residing at Queens Park, Kilburn, London, N. 5 W., England, have invented certain new and useful Improvements in Signaling Apparatus, of which the following is a specification.

This invention relates to a signal apparatus and particularly to an audible signal for use between ships at sea, between ships and the coast and wherever audible signals may be used, and to this end the invention has for its primary object to provide a simple 10 apparatus that can be operated automatically or manually to produce one or more blasts upon sound producing instruments having different and distinct tones which may be distinguished by the hearer and convey the information, particularly in foggy weather of the position of the vessel carrying this apparatus and the direction in which said vessel is steering.

Another object of the invention is to provide an apparatus that will cause one, two or more blasts of equal length and at predetermined intervals to be sounded upon horns, whistles, or other suitable instruments each having a tone readily distinguishing it from 15 the others so that the order in which the blasts are sounded may be easily understood at a distance and the information to be conveyed by the blasts or series of blasts readily interpreted according to a previously determined code.

A further object of the invention is to provide an apparatus for the purpose set forth with a rotating drum, wheel or cylinder timed to revolve within a given period 20 of time and having on its peripheral surface a number of projections each of the same length and arranged in groups, the projections of each group being equally spaced from one another. The projections further- 25 more are arranged each in a different plane perpendicular to the axis of the cylinder so that one, two or more may act in succession upon a rocking member for the purpose of actuating a cable or lanyard leading to the 30 sound-producing instruments.

With the above as the principal objects in view the invention consists in the novel construction, combination, and arrangement of parts hereinafter described, pointed out in

the appended claims, and illustrated in the 55 accompanying drawings, in which—

Figure 1 is a side elevation of the improved apparatus for operating sound producing instruments,

Fig. 2 is a front elevation of the same 60 mechanism,

Fig. 3 is a top plan view of the apparatus,

Fig. 4 is a sectional view on the line 4—4 of Fig. 3 of a detail of the invention, and

Fig. 5 is a cross sectional view on the line 65 5—5 of Fig. 4.

In the drawings, the frame of the apparatus is formed of a front standard 10 and a rear standard 11 placed in parallel relation and a suitable distance apart to include the 70 mechanism therebetween. About midway the height of the standards 10 and 11 there is provided in each a bearing for a horizontal shaft 12 upon which is fixed a drum or cylinder 13, said shaft and drum being rotatable by a pulley 14 keyed on one end of the shaft and driven by a belt 15 from any suitable source of power and geared to turn the drum or cylinder 13 one complete revolution in a minute or any other preferred period of 80 time. The standards 10 and 11 are each divided below the bearing or shaft 12 as shown at Fig. 1 into two downwardly inclined legs 16 forming as shown an A shaped frame whereby greater steadiness is given 85 to the standards. The upper end of each standard above the periphery of the drum or cylinder 13 is divided into three branches of trident shape, the central branch 17 being slightly higher than the lateral branches 18 90 and 19. Between the branches 17 of the two standards there extends a horizontal plate 20 fixed at its ends to the branches 17. A similar plate 21 connects the branches 18 while the plate 22 joins the branches 19. Besides 95 connecting the upper ends of the standards 10 and 11, these plates support slides 23, 24 and 25 for a purpose hereinafter described.

The drum or cylinder 13 is provided with a number of radial projections 26 on its 100 peripheral surface, here shown as four in number and placed all within the space of a semi-circumference of the drum so that the four projections will operate the sound producing mechanism within a half rotation of 105 the drum and remain quiet the other half. These four cams or projections do not lie all in the same plane of rotation but each

projection is in a separate plane as indicated clearly in Figs. 2 and 3, an arrangement whereby one, two, three or four blasts may be sounded as desired with little or no trouble by said mechanism. These four projections are preferably placed at the front end of the drum or cylinder 13, similar projections 27, here shown as three in number being formed in like manner on the rear end 10 of the cylinder. At the center of the cylinder are four cams or projections 28 all double the length of the projections 26 and 27 and equally spaced around the circumference of the cylinder in the same plane 15 with short intervals therebetween, these cams serving to sound long, equally spaced blasts continuously as the drum or cylinder 13 rotates.

A short distance below the plate 21 is a 20 horizontal shaft 29, the ends of which are journaled in the branches 18 of the standards 10 and 11. Slidable longitudinally on the shaft 29 is a tappet comprising a sleeve 30 from the ends of which there depend two 25 arms 31, the lower ends of which rotatably support a roller 32 adapted to bear on one or all of the projections or cams 26, the number of cams engaging the roller depending upon the position of the roller with relation 30 to the drum 13. The shaft 29 may be square in cross section or may have a groove extending from end to end thereof as shown in the drawings in which groove 33 there projects a pin or key 34 from the sleeve 30 35 by means of which the tappet is guided longitudinally on the shaft 29 while the latter rocks whenever the tappet 32 is elevated by one or more of the cams 26. Near the forward end of the shaft 29 is a downwardly 40 extending arm 35 that is fixed on the shaft to rock therewith, and has on its lower end a quadrant 36 the outer or convex face of which quadrant is grooved as at 37 to receive a small rope or lanyard 38, one end of which 45 is attached to an eye 39 at the lower end of the arm 35, and passing therefrom in the normal position of the parts around a groove pulley 40 journaled on a bracket 41 projecting outwardly from 50 the standard 10. The lanyard 38 after passing around the pulley 40 extends in the most direct manner to a sound producing instrument such as a horn or whistle operated by air, steam, or other fluid. Projecting upwardly from the sleeve 30 is a 55 quadrant shaped plate 42 that slides freely in a notch 43 in a web or plate 44 on the under side of the slide 24 movable on the plate 21. By this construction the slide may 60 be moved longitudinally on the plate 21 into position to cause the roller 32 to extend sufficiently far over the drum 13 to be engaged by one, two, or more cams or projections 26. The slide is retained in position 65 to maintain the roller in engagement

with the proper number of cams by means of a pin 45 secured on one end of a resilient arm 46, the opposite end being attached at 47 to the top of the slide. The pin 45 has a spherical finger piece 48 by means of which 70 the pin may be raised from any one of a series of holes 49 in the plate 22 to disengage the slide from the plate and permit the latter to be moved longitudinally thereon and by engaging the pin in another of said 75 holes locking slide in the determined position.

Besides the tappet 50 and the slide 24 just described mounted to coöperate with the cams 26, there is a second tappet 51 and 80 slide 25 also arranged in connection with a shaft 52 and plate 22 to be actuated by the cams 26. This slide 25 as previously stated is mounted on the plate 22 below which is a shaft 52 that carries the tappet 51. This 85 tappet and slide are similar to the tappet and slide previously described and therefore no detail description will be required. Keyed on the front end of the shaft 52 is a downwardly projecting arm 53 on the end 90 of which is a quadrant 54 similar to the quadrant 36 and grooved in a similar manner on its convex face for a lanyard 55 that is fixed at one end to said quadrant and after passing around a roller 56 supported by a 95 bracket 57 passes to a sound producing instrument that differs in pitch and in quality from the sound producing instrument operated by the lanyard 38.

The plate 20 attached to the central 100 branches 17 of the standards 10 and 11 carries a slide 23 similar to the slide 24 and below said slide is a tappet 58 supported on a shaft 59 journaled in the branches 17. This tappet as with the previously described tappets is slidable on its supporting shaft and rocks said shaft when the tappet is actuated by any one or all of the cams 27 on the rear end of the drum 13. An arm 60 fixed on the shaft 59 and extending downwardly 105 has a quadrant 61 on its lower end, this arm and quadrant being similar to the arms 35 and 53 with their quadrants previously described. A lanyard 62 is secured to the quadrant and passing about a roller 63 extends to a sound producing instrument that differs in quality and pitch from the instruments operated by the lanyards 38 and 55. From what has been said it is apparent that the cams 26 on the front end of the cylinder 120 13 are adapted to actuate two tappets each controlling a sound producing instrument that differs from the other both in pitch and quality, while the cams 27 operate a tappet that actuates a third sound producing instrument which differs in quality and pitch from the previously mentioned instruments. It is therefore clear that by properly adjusting the tappets with relation to their operating cams on the drum 13 a great number 125 130

of combinations can be produced. These combinations differ in the number of successive blasts produced by one or more sounding instruments and are readily distinguished by the quality of sound by the pitch and by the number of blasts and a simple code can be easily arranged to indicate to all persons within ear shot of the signal the direction in which the vessel carrying 5 the signal is sailing and other information which it is desirable to convey to other vessels and to the coast stations. As an example of sound producing instruments the lanyard may be connected to operate a deep 10 toned whistle when the tappet 50 is actuated, the lanyard 55 will operate a siren when actuated by the tappet 51, while the lanyard 62 operated by the tappet 58 will cause a shrill pitched whistle to sound. 15 These three instruments so clearly and easily distinguished one from the other will enable code signals to be heard with little or no confusion.

In connection with the signals hereinbefore described there is provided a fog signaling apparatus for use particularly when a vessel is approaching the shore and sailing within a harbor. This signaling mechanism comprises the cams 28 which as shown are 20 divided into four equally spaced cams around the drum 13. If desired this may be one continuous cam or instead of four, there may be two or three cams on the drum so as to produce one long continuous sound 25 or a series of two, three or four equally spaced sounds within a predetermined time. Either the deep toned whistle or the siren may be operated by moving the tappets 50 or 51 into position to be actuated by the 30 cams 28 but preferably smaller tappets such as 64 & 65 slideable on the shafts 29 and 52 are employed. These tappets each carry a roller 66 and are operated each by a slide 67 carried by the horizontal plates 21 and 22. 35 A quadrant 68 on the tappets 64 and 65 similar to the quadrant 42 enables the tappets to be moved longitudinally on their supporting shafts whenever the slides 67 are moved on the plates 21 and 22. Locking 40 pins 69 are mounted on the slides to engage holes 70 in the horizontal plates for securing the tappets in position to be operated by the cam 28 or out of engagement with said cams as desired. The tappets 64 and 65 are 45 keyed to the shafts 29 and 52 respectively and slide endwise on said shafts so that when either of these tappets is operated by the cams 28 the lanyard operating arms 35 and 53 will be operated to sound the deep-toned whistle or the siren, it being understood that the tappets 50 and 51 will under 50 these conditions be moved beyond the drum so as to be inoperative.

What I claim is:

65 1. A signaling apparatus comprising a

rotatable drum having groups of cam projections on its peripheral surface, a pair of tappets each having a broad contact end adapted to be moved into position over a group of cam projections to be operated by 70 one or more of the projections of said group, a third tappet also having a broad contact end movable into position to be operated by one or more cam projections of another group of cams, and a swinging arm 75 operated by each of said tappets adapted to be connected each to an independent sound producing instrument for causing said instrument to speak when the tappet is operated. 80

2. A signaling apparatus comprising a rotatable drum having a plurality of circumferentially spaced cam projections on the periphery thereof arranged in groups, each of said cams being arranged in a different 85 plane perpendicular to the axis of the drum, a plurality of tappets, each tappet being provided with a broad roller adapted to be moved into operative engagement with one or more cams of a group of cams, and means 90 actuated by each of said tappets to cause a sound producing instrument to speak when the tappet is operated.

3. A signaling apparatus comprising a rotatable drum having a plurality of circumferentially spaced cam projections on the periphery thereof arranged in groups, each of said cams being spaced laterally from one another, a plurality of tappets each 95 adapted to be moved laterally entirely over the periphery of said drum irrespective of the position of the other tappets, a broad roller on each tappet enabling said tappet to be engaged by one or more of said cam projections as the drum rotates, an arm actuated by each of said tappets, and a connection between each arm and a sound producing instrument to cause said instrument to speak when the tappet is operated. 100

4. A signaling apparatus comprising a rotatable drum having a plurality of circumferentially and laterally spaced cam projections on the periphery thereof, a plurality of tappets each mounted upon a horizontal 105 shaft and adapted to be moved longitudinally on said shaft entirely across the drum irrespective of the positions of the other tappets, each tappet being keyed to the shaft to rock the latter when the tappet is operated, means for moving each tappet over 110 said drum to be engaged by one or more cam projections of a group, an arm fixed on each rock shaft to move therewith, and a connection from each arm to a sound producing instrument for causing the latter to speak 115 when the controlling tappet is operated. 120

5. A signaling apparatus comprising a rotatable drum having circumferentially and laterally spaced cam projections on the periphery thereof arranged in groups, a plu- 130

rality of rock shafts exterior of said drum and parallel with the axis thereof, a tappet mounted on each shaft to rock the same and movable longitudinally thereof across the 5 drum irrespective of the positions of the other tappets, a slide above each tappet connected thereto to move the same upon its shaft, locking means on each of said slides for fixing the tappet in position to be operated by one or more cam projections of a group, an arm fixed to each shaft and a lanyard connected to each arm and adapted to operate a sound producing instrument to cause the latter to speak when the tappet 10 is operated.

6. A signaling apparatus comprising a rotatable drum having circumferentially and longitudinally spaced cam projections on the periphery thereof arranged in groups, 20 a plurality of tappets operated by said cam groups, each of said tappets comprising a sleeve slidable on a horizontal shaft and adapted to rotate said shaft, arms depending from said sleeve, a roller pivotally carried 25 by said arms and adapted to engage one or more cams of a group, a quadrant-shaped plate projecting upwardly from said sleeve, a slide in engagement with said plate for moving the tappet over the drum into engagement with one or more cams and lock 30

the same after being moved to a predetermined position, and means fixed on the shaft adapted to be connected to a sound producing instrument for causing the latter to speak when the tappet is operated. 35

7. A signaling apparatus comprising a drum having a plurality of spaced cam projections on the periphery thereof arranged in groups, a plurality of tappets each adapted to be operated by one or more cams of a group, 40 said tappets being longitudinally movable on a rock shaft over the periphery of the drum and having means for locking said shaft, a plate parallel with each of said shafts, a slide longitudinally movable on each plate and adapted to be connected with a tappet for moving the latter on a shaft, locking means on each slide for fixing the tappet in a determined position, an arm fast on each shaft, and a lanyard connected to 45 each arm and adapted to actuate a sound producing instrument for causing the latter to speak when the tappet is operated.

In testimony whereof I affix my signature in presence of two witnesses.
